REMOTE CONTROL DEVICE

Irving Ball, Elizabeth, N. J.

Application November 28, 1932, Serial No. 644,744

1 Claim. (Cl. 250—40)

This invention relates, generally, to remote control devices; and the invention has reference, more particularly, to a novel, simply constructed remote control device for operating the tuning dial of a radio receiver at a distance from the receiver and for operating other apparatus from a distance.

Remote control devices heretofore employed for operating the tuning dials of radios and for other uses have been of more or less complicated nature, rendering the same expensive to manufacture, with the result that such devices have never become popular. Furthermore, owing to the complexity of such devices heretofore used, the same are apt to get out of order in use, resulting in frequent repairs and adjustments, thereby detracting from the utility of such devices.

The principal object of the present invention is to provide a novel remote control device for operating the tuning shafts of radio receivers from a distance as well as for operating other apparatus, the said device being of extremely simple construction and entirely mechanical in its nature, the same employing cables working only under tension for transmitting the desired operating forces.

Another object of the present invention lies in the provision of a novel remote control device of the above character employing sheaves over which the power transmission cables run, one of said sheaves being located at the radio tuning shaft or other shaft to be turned and the other of said sheaves being located at the desired remote point of control.

Still another object of the present invention is to provide a remote control device of the above character which is of sturdy, strong construction, dependable in use and may be manufactured in large quantities at low cost, the same being easily and quickly installed in use.

Other objects of this invention, not at this time more particularly enumerated, will be clearly understood from the following detailed description of the same.

The invention is clearly illustrated in the accompanying drawing, in which:

Fig. 1 is a perspective view with parts broken away showing the novel remote control device of the present invention employed for operating the tuning shaft of a radio receiver.

Fig. 2 is a view in elevation with parts broken away of that portion of the control device located at the tuning shaft of the radio receiver.

Fig. 3 is a part sectional view taken substantially along line 3—3 of Fig. 2.

Fig. 4 is a plan view with parts broken away of that portion of the control device located at the remote control end of the apparatus.

Fig. 5 is an enlarged part sectional view taken substantially along line 5—5 of Fig. 4; and

Fig. 6 is a fragmentary schematic view illustrating the application of the remote control device of this invention for operating furnace dampers.

Similar characters of reference are employed in all of the above described views to indicate corresponding parts.

Referring now to Figs. 1 to 5 of said drawing, the reference numeral 1 designates a typical radio receiver having a tuning dial 2 which is illustrated as operated by the novel remote control device of the present invention. This remote control device is designated as a whole by the reference numeral 3. Control device 3 comprises a casing 4 having a semi-cylindrical upper portion and a tapered lower portion. The upper portion of casing 4 is provided with a cylindrical recess 5 extending inwardly from the front face of this casing, which recess has a sheave 6 turnable therewith.

Sheave 6 is illustrated as threaded upon a reduced extension 9 formed on the hub 7 of a tuning knob 8, which tuning knob is adapted to be mounted upon the tuning dial shaft or condenser shaft 10 of the radio receiver set. A set screw 11 is illustrated as employed to secure the hub 7 and knob 8 upon the shaft 10. The shaft 10 extends rearwardly through a circular aperture provided in the rear of casing 4 and on into the interior of receiving set 1. A collar 12 is illustrated as fixed upon condenser shaft 10 adjacent the rear surface of the casing 4 by means of a set screw 13. Collar 12 cooperates with the hub 7 of knob 8 to retain the casing 4 in desired position upon the tuning condenser shaft 10.

Sheave 6 is provided with two annular grooves 16 and 17 for respectively receiving cables 14 and 15. The end portion of cable 14 projects inwardly through a small radial aperture provided in the sheave 6 and is secured to this sheave by means of a set screw 18 that is threaded into a transverse aperture provided in the sheave 6, which transverse aperture communicates with the radial aperture through which the end portion of the cable extends, as especially shown in Fig. 3. Likewise, the end portion of cable 15 projects inwardly through a small radial aperture provided in the sheave 6 and is secured to this sheave by means of a set screw 19 that is thread-

ed into a transverse aperture provided in the sheave 6, which transverse aperture communicates with the radial aperture through which the end portion of the cable 15 extends. Cable 14 is wrapped for a number of turns about the sheave 6 and extends from this sheave through a bore 20 provided in the tapered portion of casing 4, which bore communicates with the hollow interior of a coiled wire conduit 21 forming a part of a cable conduit 22. Likewise, cable 15 is wrapped for a number of turns about the sheave 6 and extends from this sheave through a bore 23 provided in the tapered portion of casing 4, which bore communicates with the hollow interior of a coiled wire conduit 24 forming a part of the cable conduit 22. The end portion of cable 15 is wrapped about the sheave 6 in the opposite direction to the wrapping of cable 14 about this sheave. The end of cable 20 conduit 22 is attached to casing 4 by suitable clamping means such as the clamp ring 45 having a screw 46 threaded therethrough and engagging a projection 47 of the casing 4.

Coiled wire conduits 21 and 24 serve as conductors for the cables 14 and 15 and permit longitudinal movement of these cables through the cable conduit 22. The cable conduit 22 may be of any reasonable length desired and extends to the desired remote point of control, at which point is located a casing 25 which is somewhat similar in construction to that of casing 4. The end portion of cable 22 adjacent the casing 25 is illustrated as extending into and is secured within a tube 26 which is slidingly mounted within and projects outwardly from a cylindrical recess 27 provided in the casing 25.

In order to provide for expansion and contraction of the cable conduit 22 and its coiled wire conduits 21 and 24 with respect to the cables 14 and 15, the tube 26 is illustrated as urged outwardly of recess 27 by means of a compression coil spring 28. Thus, spring 28 by urging the tube 26 outwardly serves to retain the cables 14 and 15 taut at all times within the conduit 22. Tube 26 is illustrated as provided with a longitudinal slot 29 therein for receiving the inner end portion of a set screw 30, which set screw by contacting with the ends of slot 29 serves to limit movement of tube 26 with respect to the casing 25.

Cables 14 and 15 extend through inclined bores 31 and 32, respectively, provided in the casing 25 and are wound in opposite directions upon a sheave 33 turnably mounted within a cylindrical pocket 34 provided in the casing 25. A bearing pin or screw 35 extends through a central aperture provided in the sheave 33 and is threaded at 36 into the casing 25. Cable 14 is wrapped within an annular groove 37 provided in the periphery of sheave 33, whereas cable 15 is wrapped within an annular groove 38 provided in the periphery of the sheave. The end portions of cables 14 and 15 are secured to sheave 33 by set screws 39 and 40 in the same manner that the other end portions of these cables are secured to sheave 6. Sheave 33 is provided with an operating knob 41 and has an indexing member or finger 42 thereon which is adapted to sweep over a scale 43 depicted on the casing 25, which scale corresponds preferably to the scale on the dial 2 of the radio receiver.

To install the novel remote control device of the present invention, it is merely necessary to remove the ordinary tuning knob from the condenser shaft 10 and to replace the same by the

knob 8 and collar 12 of the present apparatus, after which the device is ready for use. In installing the casing 4 upon the condenser shaft 10, the tuning dial 2 of the radio set is initially set so as to correspond with the position of the indexing member 42 on the scale 43.

In use, when it is desired to adjust the setting of the dial 2 of the radio receiver, it is merely necessary to turn the knob 41 at the remote point of control as illustrated in Fig. 1, whereupon driving tension is created in one or the other of the cables 14 and 15, depending in which direction the knob 41 is turned, resulting in the corresponding turning of sheave 6 at the radio receiver. The turning of knob 41 causes one of the cables 14 or 15 to be wound upon the sheave 33 while the other of these cables is simultaneously unwound from this sheave and a corresponding action takes place at the sheave 6, thereby effecting the desired turning of the condenser shaft 10. The cable which is being wound upon the sheave 33 at any time is the motivating cable at that time and transmits its driving force by pure tension, thereby eliminating cable distortion or kinking which is apt to occur in installations where the cable is used to transmit torque or compressive forces.

Since cables are designed primarily to transmit tensile stresses and as the cables 14 and 15 used in the device of the present invention transmit only tensile stresses, the present device has an exceedingly long life in use. Owing to the simplicity of the device of the present invention, the same is easily and cheaply manufactured and may be used for long periods without the necessity of repairs or adjustments.

In Fig. 6 the novel remote control device of the present invention is illustrated as employed for operating the damper 49 of a furnace 50. In this application of the invention, the casing 4 is mounted on the damper shaft while the casing 25 is conveniently located, as for example, upon the wall 51 of the room above the furnace 50, the knob 41' projecting outwardly from the wall for easy manipulation. The operation of the device as thus applied is much the same as when used for operating a radio receiver, the tension in cables 14 and 15 serving to turn the damper 49 from the knob 41'.

It will be apparent that the provision of knob 8 enables the turning of shaft 10 at any time without interference from the remote control device of this invention, the sheaves of which device turn idly when knob 8 is turned, as by the user standing at the radio receiver.

As many changes could be made in the above construction and many apparently widely different embodiments of this invention could be made without departing from the scope thereof, as defined by the following claim, it is intended that all matter contained in the above description or shown in the accompanying drawing shall be interpreted as illustrative and not in a limiting sense.

What is claimed is:

In a remote control device adapted for turning the operating shafts of radio receiving sets from a remote point of control, a casing arranged to be slid upon and suspended from the operating shaft of the radio set to be controlled, a sheave turnably mounted within said casing, a knob fixed on the operating shaft of the radio set, said knob having a hub secured to said sheave, a second casing adapted to be located at the remote point of control, a sheave turnable within said second casing, said second casing having a scale depicted

thereon adjacent said last named sheave, said latter sheave having an operating knob thereon for effecting the turning thereof and having a pointer thereon movable over the scale of said 5 second casing, a cable conduit interconnecting said first and second casings, a pair of cables wrapped in opposite directions on said first named sheave, said cables extending outwardly of said

first casing through said cable conduit to said second casing wherein said cables are wrapped in opposite directions about said last named sheave and spring means within said second casing and acting upon said cable conduit for causing said cables to be taut within said cable conduit.
